Letters Patent No. 2431, Dated Sept. 25. 1866. DES. 2431

Design for a Clock Case Front.

The Schedule referred to in these Letters Patent and making part of the same.

To all whom it may concern:

Be it known that we, S. F. Carter & W. W. Carter of Bristol, County of Hartford, and State of Connecticut have originally and now, and useful Design for a Clock Case Front, of which the following is a clear, full, and exact description, reference being had to the accompanying photograph, illustrations and letters of reference marked thereon.

In the accompanying illustrations a, is a circular, round, and hollow moulding or upper member of the case

b, is a circular, round, and hollow moulding or lower member of a case.

c, is a circular bead or dash.

d, is a circular bead or dash.

e, are curved or figureed embellishments.

The whole combined to produce a rich and highly ornamental Design for a Clock Case.

That the claim therefore and desire to secure by Letters Patent is the Design for a Clock Case Front substantially as shown in illustration and described.

Witnessed,
